YARN-END HANDLING DEVICE

Benjamin Grill, Valdese, N. C., assignor to
 Waldensian Hosiery Mills, Inc., Valdese, N. C.,
 a corporation of North Carolina

Application November 17, 1939, Serial No. 304,876

11 Claims. (Cl. 66—135)

This invention relates to yarn-end handling devices, useful in those circular knitting machines wherein longitudinal or supplemental yarns are incorporated in the tubular fabric additionally to the regular or knitting yarns. An example is the wrap stripe or analogous type of machine, wherein the wrap yarns, usually gathered manually in a bunch or cluster, are required to be tensioned or pulled downwardly within the cylindrical path of the fabric or stocking, during the initial stages of knitting each product, to hold the supplemental yarns taut in proper position for feeding them to the needles.

In the circular knitting of stockings, men's, women's, children's or infants', it is frequently desirable to introduce supplemental or longitudinal yarns usually of different character or color from the knitted or body yarn, for the formation of stripes, clocks or other patterns or effects, these longitudinal or stripe yarns becoming combined with the knitting yarns but without necessarily being knitted into the fabric; each body yarn in such a case being of the nature of a circular weft, while each additional or stripe yarn may be compared with a warp. As herein illustrated and designed the present invention is adapted for use in certain known makes of so-called transfer top wrap stripe circular knitting machines, but is not intended to be limited thereto. In such machines the stocking top section, which is frequently ribbed, is first knitted in another machine, and this rib-top is then transferred to the wrap-stripe machine and applied to depend from the circle of needles; the wrap yarns being subjected to tension, and then, by the wrap fingers, applied or wrapped around selected needles, from course to course, according to the design of the product.

In one heretofore prevailing practice, at the commencement of the regular knitting or following the completion of each product, the introduced or wrap yarns are handled as follows. They are gathered and bunched or twisted together and held in a cluster below the level of their feeding mechanism, and are then severed, as by scissors, from the previous product, but frequently by means of a stationary cutter mounted in a convenient fixed location at the side of the machine, to which the operator may laterally swing the previously completed stocking and yarn group to effect such severing. Thereafter the yarn cluster is removed from the cutter and attached or clipped to a weight which may hang freely and apply gravity pull to all of the several yarns of the group as is desirable to

facilitate the starting of knitting of the next stocking. One type of gravity weight used for this purpose has been provided with an upstanding extension or stem formed into a hook, and with a spring yarn clip on the weight, so that the severed yarn group can be engaged in the clip and manually wound somewhat around the shank; or the cluster might be first wound on the shank before cutting and gripping. Another plan was to tie the clustered yarns in a knot after severance and hook the weight on to the knot, so as to pull the yarns down into the cylinder in position to cooperate in the feeding of these yarns to the needles.

Under such known systems the operations of severing and applying the yarn-cluster to the holding weight have been found to be objectionable in the consumption of time necessary for these manual steps, which may aggregate into a substantial time loss and consequent production delays, especially when a single operative attends to a considerable number of knitting machines.

A further existing objection has been that there has been a substantial waste of material in that the several or many longitudinal or wrap yarns have had to be pulled down through their feeding devices to an excessive extent to permit the described cutting and weight applying operations, resulting in objectionably long loose yarn ends on each product.

The general object of the present invention is to afford a yarn-end handling device which eliminates the noted objections of delay, labor loss and yarn waste, and which is compact and convenient in handling, and effective in operation. A particular object is to simplify manipulation and dispense with the need of performing separate successive operations, namely, the pulling aside of the supplemental yarn group to a lateral point for severing, and the attaching thereto of the centrally suspended tensioning weight.

With the present invention a weighted and freely depending device is adapted to be applied to, and act upon, a single cluster of several supplemental yarns in a manner to perform the several functions of severing the cluster and thus releasing the completed product, holding or clamping the new yarn ends as a group or bunch, and pulling them down within the cylinder to dispose them in position for feeding to the needles.

Other and further objects and advantages will be explained in the hereinafter following de-

5

scription of an illustrative embodiment of the invention or will be understood by those conversant with the subject. To the attainment of such objects and advantages the present invention 5 consists in the novel yarn-end handling device for circular knitting machines, and the novel features of construction, arrangement and operation thereof, the principles of which are herein illustrated and described.

10 In the accompanying drawing

Fig. 1 is a plan view showing the top end of a yarn handling device embodying the present invention, when arranged in its upright or substantially natural operating posture.

15 Fig. 2 is a side elevation of the device shown in Fig. 1. In Figs. 1 and 2 the device is in its closed position as it will be when functioning in the machine.

20 Fig. 3 is a view similar to Fig. 2, but with the device in its open or receiving position, in which it may be so held manually, and with the upper part of the device shown in vertical section taken on the line 3—3 of Fig. 1.

25 Fig. 4 on an enlarged scale is a horizontal sectional view taken on the line 4—4 of Fig. 2, with the yarn represented by a crinkly line.

30 Fig. 5, on the same scale as Figs. 1—3, is an exploded view of the mechanical parts of which the illustrated device is constituted, with the main halves or sections of the device each shown in inside view.

35 Fig. 6 is a more or less diagrammatic figure illustrating the manner and principles of the practical use of the device in a wrap stripe circular knitting machine.

40 Referring to the drawing, the diagram Fig. 6 shows a length of tubular fabric *x*, representing the top section of a stocking, without wrap stripes, but preformed on the same or different machine. A number of supplemental or wrap 45 yarns *y* are shown, with their ends depending within the tubular path, their introduction into the fabric not having begun. These appear extending generally longitudinally downward and below the knitting level and are shown gathered or bunched into a yarn cluster *z*, to which the device 10 hereof is attached, providing gravity force to pull and hold under control all of the 50 yarns of the group. The knitting or body yarns are not shown, but there is shown a circular bank of independent knitting needles marked *a*, mounted around the periphery of a conventional needle cylinder *b*, for example of the rotary type, the cams and means for actuating the needles 55 not being shown. The knitting yarns are to be understood to be fed to the needles by conventional means, represented by the feed mechanism *c*, only partially shown.

60 The needles are shown to be standing at varying levels, and adjacent to their upper ends is illustrated a surrounding latch ring *d*, for example of the pivoted type. Carried on the latch ring are to be understood the conventional knitting 65 yarn feeding fingers, not shown; and the ring is shown as carrying a series of wrap yarn control members *e*, as sometimes employed in cooperation with the series of wrap yarn feed fingers *f*. Each finger *f* has a yarn eye at its lower end, and these fingers may be movable or 70 pivoted upon a suitable supporting member or annular carrier *g*. The conventional wrap yarn feed mechanism *h* as a whole is sufficiently herein represented merely by the support *g* and the feed fingers *f*, the balance thereof being well 75 known. The wrap yarn fingers have suitable

movements, between or around those needles which are sufficiently lifted, to wrap the additional yarn around such needles for forming the desired pattern. These general parts thus described constitute an illustrative embodiment of sufficient portions of a circular knitting machine for the explanation of the purposes, functions and operations of the present invention. The wrap yarn feed mechanism *h* and the needle cylinder *b* are to be understood as having such relative vertical separating movement, as by lifting the mechanism or head *h*, as to give access to the fabric and yarn ends when desired, as when the handling device of this invention is to be applied.

10 Referring next to the handling device 10, suspended from the grouped wrap yarns *y*, converging within the cylindrical path of the fabric, this device comprises a free body of substantial weight to provide the necessary gravity force for 15 tautening or tensioning and holding all of the individual wrap yarns. Said device is characterized in the fact that it carries means for severing the inferiorly gathered yarn cluster *z* and for gripping and holding the cluster between the 20 yarn supply and the severing point; the severing or cutting function and the clamping or holding function being thus effectively combined in the one single device, which may be operated 25 to bring about both functions through a single 30 manually movable operating member.

35 The details of construction of the device are illustrated in Figs. 1 to 5. The weighted device is preferably provided with an upstanding rod or stem *h* which is hooked at its upper end. 40 The body of the device, for operating the cutting and clamping means, is shown as openable and closable by jaw-like movements, and for this purpose is divided into two sections or parts, which are shown substantially equal but are not necessarily so. The body section 12 carries the stem *h* while the body section 13 is connected to the first section to be movable or swingable thereon; the two sections together constituting a free tensioning or tautening body of substantial weight. 45

50 The body sections 12 and 13 are shown as being movably connected or pivoted to each other by means of a pivot or pin 14, so that the sections may be swung to open position as shown in Fig. 3 or returned to normal closed position as shown in Figs. 1, 2 and 4. For simple manual operation of the device it is shown as provided with downwardly extending handle or lever members 15 and 16, on the sections 12 and 13 respectively; these extensions being externally 55 serrated as seen in Fig. 2 to afford better manual grip thereon.

60 In order to guide the swinging sections in their opening and closing movements the section 12, or rather its extension 15, is shown as formed with inward flanges 17, while the extension 16 is shown with inward flanges 18, spaced more closely together so as to be accommodated between the flanges 17, and sliding upon them with snug fit during the swinging movements. The 65 device is preferably maintained normally closed by a resilient means shown as a coil spring 19 of sufficient strength to perform effectively the operations to be described, the ends of the spring 19 seating upon short screw heads or studs 20 70 arranged between the flanges of the respective extensions 15 and 16. Squeezing the lever extensions opens the upper ends or jaws 12 and 13 of the device, and on release the spring closes it, this complete operation effecting both the 75

severing and clamping functions. The spring closing action preferably performs both functions, and certainly the clamping function, so that upon manual release the yarn cluster *z* remains held.

The main or upper portion of each of the body sections *12* and *13*, as best shown in Figs. 1 and 4, is channel-like, to provide a hollow interior accommodating the severing and gripping means. Thus the section or jaw *12* is shown as formed with a front wall or flange *22* and a rear flange *23*, while the jaw *13* is formed with a front flange *24* and a rear flange *25*. Associated with these parts is a combined clamping and severing means, which may be considered as comprising a severing means and cooperating clamping means.

The severing means considered separately is adjacent to the front flanges *22* and *24* and is shown as comprising a cutter or shear blade *27* formed or attached at the inner side of the flange *22* and a cooperating cutter or blade *28* at the inner side of the flange *24*, the two blades being shown offset to give a shearing action for cutting the yarn group, preferably during the closing movement of the device.

The gripping or clamping means consists of a pair of members, the clamping surface or wall *30* at the inner side of the flange *23* and the cooperating wall or surface *31* at the inner side of the flange *25*. Like the cutting member *28*, the gripping member *31* is extended rightwardly for cooperation with the complementary member, but in the case of the gripping member the corners are rounded, so that there is no cutting or shearing action, the yarn cluster *z* becoming squeezed or pinched between the grip members in the manner shown in Fig. 4. This is found to be more reliable and satisfactory than clamping by an abutting arrangement; the sliding pressure affording a wedging grip upon the material, preferably cushioned as will be described.

While the members of the severing and holding means might be formed integrally with the swinging sections or jaws *12* and *13* they are preferably made separately of suitably hard material and attached in the locations as shown. Thus the shearing blade *27* and the pinching wall *30* are shown attached to the flanges *22* and *23* by means of short screws *33*. Between the elements *27* and *30* is shown a block *34* attached by a screw *35*, this constituting a convenient means of detachably mounting the upstanding hooked stem *11*, when used. The cutting member *28* and gripping wall *31* are shown as mounted on the section *13* in a different manner. Instead of being positively attached by screws they are shown as pressed strongly apart by spacing members or springs *37*, one above the other, and these separators may afford a slight cushioning action improving the cooperation and life of the two shearing members, and relieving the gripping members from danger of crushing the enclosed yarns. The members *28* and *31* and the cushioning spacers *37* are shown secured in their operative positions by means of rods *38* which are extended through these elements and through the flanges *24* and *25*.

The operation of the disclosed machine and invention has been generally indicated. At or in advance of the start of each knitting operation, the invention comes into use; this in the case of a transfer top machine usually following the transfer of the top into the disclosed machine. The invention is preferably applied while the needle cylinder *b* and the mechanism *h* are relatively separated. The group of yarns *y*, perhaps

hanging free, or between the yarn supply and the previous product, are gathered together below the feed fingers *f*, forming the yarn bunch or cluster *z*, which may be somewhat twisted. Holding the yarn cluster in one hand the device *10* is held and squeezed in the other hand, opening its jaws, between which the cluster is then inserted and set well down in the passage between the jaws. Immediately the opening pressure may be relaxed, the spring *19* closing the jaws, so that in the same operation the severer *27*, *28* cuts off all of the yarns of the bunch while the clamer *30*, *31* grips the new ends between the severing point and the supply. This operation may readily be performed at a point in the length of the yarns close to the previous product and high up toward the supply, thus minimizing yarn wastage. The weighted device is then let down or drawn into the needle cylinder or fabric *x*, and the cylinder and the yarn feed mechanism are reset into operating relation. The device now hangs free, pulling taut the wrap yarns against their working tensions, not shown, provided between the fingers *f* and the yarn source. As clearly shown in Fig. 6 the yarns thus become disposed in a position for feeding by the fingers *f* to the needles. Circular knitting is now started, and at appropriate points of time the fingers *f* are moved inwardly, outwardly and otherwise to lay the wrap yarns selectively around one or two or more of the needles according to the pattern desired. The hook *11* is an optional feature. It may be hooked into the fabric of the stocking top section *x* in order to position the weighted device at the desired height, where it functions as an anchor or holding point for the bunched ends of the wrap yarns.

What is claimed and desired to be secured by Letters Patent is:

1. For use in a circular knitting machine of the kind wherein supplemental or longitudinal yarns may be incorporated with the knitting yarn in the fabric, a device for handling the ends of a group of such longitudinal yarns interiorly of the cylindrical path of the fabric, comprising a body of substantial weight adapted to depend interiorly to provide gravity force for tautening the yarns, said body carrying means for severing such group of yarns gathered in a cluster, and means for gripping and holding such yarn cluster between the supply and the severing point; and a manually operable means or handle arranged on said device to actuate both the severing means and gripping means in a single operation thereof, whereby the device may be left hanging freely within the circular path thereby to hold the group of yarn ends with the yarns under control in suitable position for feeding to the knitting needles.

2. The device as in claim 1 and wherein the body comprises two sections swingingly connected to open and close, with a spring to close them and handle extensions to open them by grasping and squeezing in opposition to the spring resistance.

3. For use in a circular knitting machine of the kind wherein supplemental or longitudinal yarns may be incorporated with the knitting yarn in the fabric, a device for handling the ends of a group of such longitudinal yarns interiorly of the cylindrical path of the fabric, comprising a body of substantial weight adapted to depend interiorly to provide gravity force for tautening the yarns, said body carrying operable means for severing such group of yarns gathered in a cluster,

and operable means for gripping and holding such yarn cluster between the supply and the severing point.

4. The device as in claim 3 and wherein the body comprises two parts swingable together and apart, with manual means to cause their opening and closing.

5. The device as in claim 3 and wherein the body comprises two parts swingable together and apart, with manual means to cause their opening and closing, and the severing and gripping means each comprises complementary members, one on each body part, and moving in mutual sliding contact.

10 6. For use in a circular knitting machine of the kind wherein supplemental or longitudinal yarns may be incorporated with the knitting yarn in the fabric, a device for handling the ends of a group of such longitudinal yarns interiorly of the 15 cylindrical path of the fabric, comprising a body of substantial weight adapted to depend interiorly to provide gravity force for holding down the yarn ends, said body carrying operable means for severing and clamping such group of yarns gathered in a cluster, and a manual means arranged to actuate the severing and clamping means to cut off the yarn cluster and hold all the 20 yarn ends between the supply and severing point.

7. The device as in claim 6 and wherein the operable means comprises complementary severing and clamping members, and the body comprises opposed sections carrying such complementary members and swingable toward each other to operate said means.

8. The device as in claim 6 and wherein the operable means comprises complementary severing and clamping members, and the body comprises opposed sections carrying such complementary members and swingable toward each other to operate said means; said manual means being arranged to swing apart said sections in opposition to a strong spring to swing them towards each other.

9. For use in a circular knitting machine, a device for handling the ends of a group of longitudinal yarns, comprising a weighted body to provide gravity force for anchoring or holding the 10 yarns, said body carrying means for both severing and clamping such group of yarns gathered 15 in a cluster, and manual means adapted to actuate the severing and clamping means in a single action.

10. The device as in claim 9 and wherein the body comprises movable parts readily openable by 20 one-hand manipulation thereof, with spring means to close the same and operate the severing and clamping means; whereby the device may be operated by one hand and the cluster inserted by the other hand.

11. For the knitting purposes described, a freely movable weight carrying a combination means manually operable both to sever and clamp in one operation a bunch of yarns applied thereto, and having sufficient gravity thereupon to tauten operatively the bunch of yarns.

BENJAMIN GRILL.
